UNITED STATES PATENT OFFICE.

FREDERICK N. CRONHOLM, OF SUNNYSIDE, WASHINGTON.

MOLD FOR CONCRETE PIPE.

1,103,270.

Specification of Letters Patent. Patented July 14, 1914.

Application filed June 7, 1911. Serial No. 631,738.

To all whom it may concern:

Be it known that I, FREDERICK N. CRONHOLM, a citizen of the United States, residing at Sunnyside, in the county of Yakima 5 and State of Washington, have invented a new and useful Mold for Concrete Pipes, of which the following is a specification.

This invention has reference to improvements in molds for concrete pipe, and is designed more particularly for the manufacture of concrete pipe of comparatively small diameter, the object of the present invention being to provide a mold of such construction that concrete pipe may be economically formed of wet mixtures and eliminating certain of the objectionable features heretofore inherent in the manufacture of concrete pipe of small diameters in molds as ordinarily constructed.

It is customary to manufacture concrete pipe of small diameter with what is commonly known as a dry concrete mixture, wherein there is so small a percentage of water that the mixture when ready for tamping contains about the same amount of moisture as does damp earth and is, therefore, very porous. Such a mixture is termed a dry mixture as compared with the wet mixtures which because of the great amount of water present have received the name of wet or sloppy mix.

The dry or damp mixture is extensively used for various reasons, as, for instance, the output is governed by the amount which can be mixed and not by the size of the plant, the forms can be removed as soon as filled, and, therefore, may be used over again immediately, the forms require neither oiling nor cleansing, and the economy with which they may be made. However, a pipe formed of the so-called dry concrete is very porous and the manufactured product is so frail that the percentage of breakage due to handling and shipping is large. Furthermore, it will not withstand a hydraulic pressure greater than a ten or fifteen foot head, depending on the diameter of the pipe, so that for greater heads flumes and wooden pipes replace pipes made of the damp concrete mixture, but such flumes and wood pipe are of only temporary character. Furthermore, the damp or dry concrete mixture does not permit the use of reinforcements. Concrete pipe made of the wet mixture is greatly superior in strength and admits of

the use of reinforcements. Again, with a wet mix a surface far superior to that obtained from dry concrete may be secured, so that pipe may be made of materially smaller diameter, and because of the comparatively small friction, may still furnish as large a quantity of water as a larger pipe made of the dry mix, this resulting in a saving of material, and, furthermore, the pipe so made is lighter to handle owing to the reduced diameter. With the wet mix a coarser aggregate may be used in the manufacture of the pipe, whereby there is a saving in the quantity of cement necessary of nearly fifty per cent. Because of the greater strength of the pipe, the sections may be of greater length.

With the present invention, and because of the lighter form of the pipe with superior strength over pipe made by the dry concrete method, the cost per foot of pipe laid in place need not be much if any greater than that of pipe made by the dry process, while the actual strength of the pipe is much greater. Of course, small pipe can be made of wet concrete by the use of forms now on the market, but the manufacture is prohibitive because of the high cost of the forms and the necessity of having a great number of the forms, since they must be left in place until the concrete has solidified sufficiently, and, furthermore, the breakage due to the removal of the forms is comparatively large.

With forms constructed in accordance with the present invention, the cost per form is so small that the number of forms necessary is not of great moment as compared with the ordinary forms used in the wet concrete process, so that the far superior pipe made from wet concrete over that made from dry concrete can be produced at about the same price as pipe made from dry concrete. Moreover, the forms of the present invention greatly facilitate and simplify the operation of molding and to a commensurate extent cheapen the cost of manufacture.

The invention will be best understood from a consideration of the following detailed description, taken in connection with the accompanying drawings forming a part of this specification, with the understanding, however, that the invention is susceptible of various changes and modifications and that the drawings while showing practical em-

bodiments of the invention, by no means disclose all the practical embodiments which the invention may assume.

In the drawings, Figure 1 is a longitudinal diametric section of a form constructed in accordance with the invention. Fig. 2 is a plan view of the form with the filling hopper omitted. Fig. 3 is a cross section of a portion of the outer form at the division line. Fig. 4 is a longitudinal section of a portion of a form showing a construction of lining for large molds. Fig. 5 is a longitudinal diametric section of the upper end of a form constructed in accordance with the present invention, and drawn to a larger scale than Figs. 1 and 2, the showing of Fig. 5 being of a slightly modified form of the invention. Fig. 6 is a diametric section of a portion of the lower end of the form also showing a modification of the invention.

Each form is composed of outer and inner members, the form being designed for the casting of pipe sections. The outer form is made up of a series of bars or slats 1, and the inner form of a like series of bars or slats 2, each bar or slat 1 tapering from a wide portion 3 toward each end, and each bar or slat 2 tapering from a like wide portion 4 toward each end, and in each instance the wide portion is shown as being nearer one end of the respective bar or slat than the other end. The taper portion of the respective bar or slat is confined to one longitudinal edge, while the other edge is straight or shaped in conformity with the respective outer or inner surface of the pipe section to be formed. As the pipe sections are usually straight, it will be assumed for convenience of description that the mold is to be used for the purpose of making straight pipe of even thickness throughout or to points adjacent the ends.

The slats 1 and 2 are generally segmental in cross section and the slats 1 are joined at the ends by bands 5, 6, respectively, both bands being broken at one point so that the slats may be spread out or assembled in a circular series. These bands 5 and 6 may be made of leather or other flexible material, and even in some cases of flexible metal.

The straight edges of the slats 1 are covered by a web 7 of rubber, preferably in the form of rubber cloth, so that the surface of the web away from the slats 1 is a waterproof surface non-adherent to wet cement.

Enough of the slats 1 are employed to form a circular series of the required diameter with the slats close together, and when the outer member of the mold is assembled the slats are substantially radial. The rubber web 7 is divided longitudinally, so that the outer member of the mold may be opened, and, if desired, laid flat, and when the outer member of the mold is assembled

in circular form, the edges of the web 7 are brought substantially together, both edges projecting beyond adjacent ones of the slats 1.

The free ends of the web 7 are secured to strips 8, 9, respectively, which together may be of a thickness to substantially fill the space between the end slats 1 of the series, but the free edges of the web 7 are so secured to the strips 8 and 9 that where these edges meet will be in overlying relation to the edge of one of the strips, say the strip 8, in such manner that the joint will not leak cement, since it is backed up by such strip 8, although one of the ends of the web is not directly connected to such strip 8.

The slats 2 are connected at the end by bands 10, 11, respectively, and these bands may also be broken at one point to admit of expansion and contraction of the series of slats 2, which together are designed to form the inner member or core of the mold.

The web 7 is applied to the several slats 1, while adapted to the exterior of the core constituted by the straight edges of the slats 2, these edges being the outer edges when the core is assembled, there is applied an endless sleeve 12 of rubber, preferably in the form of rubber cloth, and this sleeve 12, as well as the web 7, may, if desired, be backed up or reinforced in any suitable manner.

The core made up of the slats is expanded by means of interiorly applied hoops 13, 14, respectively, while the exterior portion of the mold is contracted by exteriorly applied hoops 15, 16, respectively, these hoops being of proper size to engage those tapered portions of the respective slats 1 and 2 between the wide portions thereof and the narrow ends secured to the respective bands 5 and 10. The hoops 13, 16 may be made of metal of suitable size and preferably are made of metal of substantially circular cross section as facilitating both the application and removal of the hoops.

In the structure shown in Fig. 1 there is provided a basic ring 17, it being customary to set the mold upright and introduce the mix at the top. This ring is formed with an annular peripheral foot 18 and with respective ledges 19 and 20 for supporting the slats 1 and 2, the lower narrow ends of the slats 1 resting on the ledge 18 and the lower narrow ends of the slats 2 resting on the ledge 20. The ring is formed with annular shoulders 21, 22, respectively, which limit the inward movement of the outer member of the mold and the outward movement of the core at the lower ends thereof, and where a bell end is to be made the shoulder 22 may be formed on the inner edge of an annular flange 23 shaped to form an annular groove constituting the bell of the corresponding end of the pipe. The upper end of the outer member of the mold has applied

thereto a ring 24 which may be provided with an outwardly flaring flange 25, the ring 24 limiting the inward movement of the upper ends of the slats 1. The upper ends of 5 the slats 2 are encircled by a ring 26 which may extend to some distance above the tops of the slats, and this ring determines the outward movement of the corresponding ends of the core slats. The ring 24 with its 10 flaring flange 25 is adapted to receive an annular hopper 27 and the upper end of the ring 26 is provided with a cover plate 28.

When an exceedingly long section of pipe is to be made, it is advisable to use a rubber 15 sleeve or jacket 12 in two or more sections, as indicated at 12^a and 12^b in Fig. 4, and it is of course apparent that the whole mold may be made in two or more longitudinally disposed sections when the mold is of such 20 a length that the handling of long sections would be troublesome. It is not necessary that the straps 5, 6, 10 and 11 be fastened to the taper edges of the slats 1 and 2, for these straps may be inset in kerfs cut in the 25 corresponding ends of the slats, as indicated at 5^a and 10^a in Fig. 5, and 6^a and 11^a in Fig. 6. Again, the ring or footing 17 may be omitted and the bottom ends of the outer member of the mold and the core may rest 30 upon a suitable flat surface and the space between the web 7 and sleeve 12 may receive a layer 29 of sand, upon which is placed a ring 30 of heavy paper or cardboard, and in the case of the formation of 35 a bell at the end of the pipe, a suitable shaped ring 31 of rubber or having a facing of rubber is lodged upon the ring 30 and against the sleeve or jacket 12.

It is to be observed that the mold is of 40 skeleton type and is not only light, but may be cheaply constructed, so that a comparatively large number of such molds may be made at the cost of a single heavy metal mold, such as is commonly employed in concrete pipe manufacture. Furthermore, by making the sleeve or jacket 12 of rubber or of a rubber faced material without joint or lap, the interior of the pipe is finished 45 smooth, it not being material as to the outer portion of the pipe, for it is the inner wall of the pipe with which water or other fluid is brought into contact, and because of the extreme smoothness of the inner wall of the pipe due to molding the cement against the 50 rubber surface, the frictional resistance is reduced to a minimum and consequently a pipe of considerably smaller diameter than the pipes as ordinarily made may be employed to conduct the same amount of fluid, 55 such as water. Moreover, the rubber faced sleeve obviates the necessity of either oiling or cleaning the molds.

When the mold has been set up, the outer portion of the mold may be centered with 60 relation to the core with sufficient accuracy

by pushing it in one direction or the other to cause the space between the inner wall of the outer section of the mold and the outer wall of the core to be of substantially even thickness throughout, or the two walls defining the molding space are in substantially concentric relation one to the other.

The wet mix is introduced into the hopper 27 and flows into the molding space, being prevented from falling into the interior of the hollow core by the cover 28. When the mold is approximately full, the ring 24 may be removed and the filling completed, leaving the corresponding end of the pipe in a finished condition. When the cement mix 70 has sufficiently set the hoops 13, 14, 15 and 16 may be removed permitting the core to collapse, so that its diameter is reduced and it may then be readily removed, while the outer portion of the mold may be separated 75 at the junction point and readily removed from the exterior of the molded pipe. Now the sleeve or jacket 12 being of a flexible nature is readily folded on itself and is thereby peeled off of the interior of the pipe 80 and removed without trouble. There thus is formed a pipe with a very smooth interior and the exterior may have thereon a layer of paper which may be introduced in position to engage the web 7 and this paper 85 may remain on the pipe strengthening it to a commensurate extent and preventing injury to the exterior of the pipe during shipment. Such layer of paper is indicated at 90 32 in Fig. 3. The surfaces with which the cement mix engages being non-adherent to the wet mixture, require no cleaning and may be immediately again used as soon as 95 they are removed from the set pipe previously cast. The web 7 is fastened to the 100 strips 8 and 9 only, and therefore the slats 1 may be removed promptly for the web 7 will hold the material until set sufficiently. The ring 26 is to remain in the end of the 105 pipe section to enter the bell end of the next 110 section in order in a line of laid pipe sections.

What is claimed is:—

1. A mold for the manufacture of concrete pipe, comprising expansible and collapsible 115 inner and outer members, each composed of a series of slats each tapering along the edge remote from the mold chamber, with flexible bands joining the ends of the slats of each member together, hoops adapted to the taper edges to expand the inner member and contract the outer member, and limiting means for the respective ends of the mold members, constructed to operate in opposition to the hoops.

2. A mold for manufacturing concrete 120 pipe, comprising expansible and collapsible inner and outer members each composed of a series of slats tapering along the edges remote from the mold chamber, with flexible 125

126

bands at the ends joining the slats of each member together and having their continuity broken to permit the laying out flat of the mold members, hoops adapted to the tapered edges to expand the inner member and contract the outer member, and limiting means for respective ends of the mold members constructed to operate in opposition to the hoops.

10 3. A mold for the manufacture of concrete pipe comprising expandible and collapsible inner and outer members, each composed of a series of slats each tapering along the edge remote from the mold chamber, with flexible bands joining the ends of the slats of each member together, hoops adapted to the taper edges to expand the inner member and contract the outer member, and limiting means for the respective ends of the mold members constructed to operate in opposition to the hoops, said limiting means comprising a basic member with shoulders for the lower ends of the respective mold members, and rings for the upper ends of the respective mold members.

15 4. A mold for the manufacture of concrete pipe comprising expandible and collapsible inner and outer members, each composed of a series of slats each tapering along the edge remote from the mold chamber, with flexible bands joining the ends of the slats of each member together, hoops adapted to the taper edges to expand the inner member and contract the outer member, and limiting means for the respective ends of the mold members constructed to operate in opposition to the hoops, said limiting means comprising a basic member with shoulders for the lower ends of the respective mold members, and rings for the upper ends of the respective mold members, the limiting ring for the upper end of the inner mold member being elongated axially to project therebeyond and to be retained by and extend beyond the corresponding end of the molded pipe section and constitute an entering member for the bell end of a matching pipe section.

20 5. A mold for the manufacture of concrete pipe comprising expandible and collapsible inner and outer members each composed of a series of slats tapering along the edge remote from the mold chamber, retaining means for the respective ends of the mold members for determining the extent of expansion and contraction, hoops adapted to the tapering edges to expand the inner member and contract the outer member, a sleeve of fabric nonadherent to concrete and constructed to envelop the inner member, and another sleeve of fabric nonadherent to concrete and constructed to line the inner wall of the outer member.

25 6. A mold for the manufacture of concrete pipe comprising expandible and collapsible inner and outer members each com-

posed of a series of slats tapering along the edge remote from the mold chamber, retaining means for the respective ends of the mold members for determining the extent of expansion and contraction, hoops adapted to the tapering edges to expand the inner member and contract the outer member, a sleeve of fabric nonadherent to concrete and constructed to envelop the inner member, and another sleeve of fabric nonadherent to concrete and constructed to line the inner wall of the outer member, the second-named sleeve of fabric having its continuity broken and provided at the meeting edges with slats adapted to lodge between adjacent slats of the outer mold member.

30 7. A mold for the manufacture of concrete pipe comprising an expandible and collapsible core and an exterior contractible mold member, each made up of a connected series of slats with those of the core tapering on the inner edge from one end toward the other and those on the outer mold member tapering on the outer edge from one end toward the other, limiting devices for the ends of the respective mold members, and hoops adapted to the taper edges of the mold members to enter the core from one end and encircle the outer mold member from the corresponding end and force the respective members into engagement with the respective limiting devices.

35 8. A mold for the manufacture of concrete pipe comprising an expandible and contractible core formed of longitudinally disposed slats connected at opposite ends by flexible connecting bands, an outer mold member comprising longitudinally disposed slats joined at the opposite ends by flexible connecting bands, the inner edges of the slats of the core and the outer edges of the slats of the outer member tapering from one end toward the other, hoops adapted to the taper edges of the core and outer member, a shouldered ring for receiving the lower ends of the core and outer member, respectively, and constructed to serve as a limiting member therefor in opposition to the action of the hoops, a ring adapted to the upper, inner edge of the outer member, and a ring adapted to the upper, outer edge of the core, and constructed to serve as limiting members therefor in opposition to the hoops.

40 9. A mold for the manufacture of concrete pipe comprising an expandible and contractible core formed of longitudinally disposed slats connected at opposite ends by flexible connecting bands, the inner edges of the slats of the core and the outer edges of the slats of the outer member tapering from one end toward the other, hoops adapted to the taper edges of the core and outer member, a shouldered ring for receiving

the lower ends of the core and outer member, respectively, and constructed to serve as a limiting member therefor in opposition to the action of the hoops, a ring adapted to the upper inner edge of the outer member, and a ring adapted to the upper, outer edge of the core, and constructed to serve as limiting members therefor in opposition to the hoops, the core being provided with a removable flexible fabric sleeve nonadherent to concrete, and the outer mold member being provided with a similar sleeve having its circumferential continuity broken and provided with slats at the meeting edges with one edge of the sleeve extending beyond the respective slat a distance to engage the other slat.

10. In a mold for the manufacture of concrete pipe, a mold member composed of

a series of slats joined at the ends by flexible bands each having its continuity broken to permit laying out of the series of slats and its assemblage into inclosing relation to a mold chamber, and a lining for the mold member comprising a sheet of fabric non-adherent to concrete, said sheet of fabric having its circumferential continuity broken and at the edges provided with slats adapted to lodge between the meeting edges of the said mold member when in operative position.
